(57) **CLAIM**

The ornamental design for a filter assembly stand, as shown
and described.

DESCRIPTION

FIG. 1 is a first perspective view of an embodiment of the
filter assembly stand of the present invention.

FIG. 2 is a second perspective view of an embodiment of the
filter assembly stand of the present invention.

FIG. 3 is a front view of an embodiment of the filter
assembly stand of the present invention.

FIG. 4 is a rear view of an embodiment of the filter assembly
stand of the present invention.

FIG. 5 is a left-side view of an embodiment of the filter
assembly stand of the present invention.

FIG. 6 is a right-side view of an embodiment of the filter
assembly stand of the present invention.

FIG. 7 is a top view of an embodiment of the filter assembly
stand of the present invention.

FIG. 8 is a bottom view of an embodiment of the filter
assembly stand of the present invention; and,

FIG. 9 is a view of an embodiment of the filter assembly
stand of the present invention illustrating environmental
context holding three filter unit assemblies together.

The view labels used herein to denote, front, rear, left-side,
right-side, top and bottom views are for convenience only
and should not be interpreted as limiting the orientation of
the bracket.

The broken lines in the Figures are for illustrative purposes
